UNITED STATES PATENT OFFICE.

JOHN WILLIAM SMITH, OF CHICAGO, ILLINOIS.

DETACHABLE HEEL.

1,313,026.

Specification of Letters Patent. Patented Aug. 12, 1919.

Application filed April 25, 1918. Serial No. 230,667.

To all whom it may concern:

Be it known that I, JOHN WILLIAM SMITH, a citizen of the United States, and a resident of the city of Chicago, county of Cook, and 5 State of Illinois, have invented certain new and useful Improvements in Detachable Heels, of which the following is a specification.

My invention relates to improvements in 10 detachable heels, and has for its object the production of a device of this character which will permit of ready and expeditious attachment or detachment and which, when detached, will be held firmly in position. A 15 still further object is the production of a heel, as mentioned, which will be of durable and economical construction and highly efficient in use.

Other objects will appear hereinafter. 20 The invention consists in the combinations and arrangements of parts hereinafter described and claimed.

The invention will be best understood by reference to the accompanying drawings 25 forming a part of this specification, and in which;

Fig. 1 is a partial sectional side elevation of the rearward portion of a shoe equipped with a heel embodying the invention.

30 Fig. 2 a partial sectional perspective view of the heel detached.

Fig. 3 a section taken on line 3—3 of Fig. 2.

Fig. 4 a bottom plan view of the heel, 35 and

Fig. 5 a detail section taken on substantially line 5—5 of Fig. 2.

The preferred form of construction as 40 illustrated in the drawings comprises a heel body 6 of rubber or other suitable resilient material. Embedded in the heel body 6 adjacent the upper side thereof and adjacent the periphery of the heel body is an annular member 7 formed of wire. Also embedded in the heel body 6 adjacent the upper side thereof is a substantially centrally positioned resilient cross piece or plate 8, the ends of which embrace the opposite sides of the member 7, being preferably 45 wrapped around the same as clearly seen in Figs. 2 and 3.

Secured rigidly to the plate 8 is a screw 9 which projects exteriorly from the upper side of the heel body substantially centrally 50 thereof, said screw being adapted, in the application of the heel to a shoe, to pierce or

be screwed into the rearward or heel portion of the shoe as clearly seen in Fig. 1.

The heel body 6 is of such form that normally the upper side thereof is concave and 60 the under side thereof convex. This being so, when the screw 9 is threaded into a shoe, in applying the heel thereto, the plate 8 will be caused to flex upwardly thereby bringing the central portion of the upper surface of 65 the heel body into contact with the under surface of the shoe. This will result in the plate 8 being placed under compression, the compression or resiliency of the plate serving to constantly force the peripheral 70 portions of the heel into snug engagement with the under side of the shoe. Thus a snug connection between the heel and the shoe will always be maintained.

In order to lock the heel body against 75 accidental retrograde rotation after the heel body has been applied, the member 7 is formed at the front and the rear of the heel body, with upwardly extending exteriorly projecting lugs 10, which are adapted, when 80 the heel body is in proper operative position, upon the shoe, to engage with sockets 11 formed in the under side of the shoe as clearly seen in Fig. 1. To further aid in holding the heel body against retrograde 85 rotation on the upper side thereof is formed a net work of furrows, such net work insuring a firm and close connection between said surface of the heel body and the adjacent 90 surface of the shoe.

Embedded in the under surface of the heel body 6 are two plugs 12 of frictional material formed preferably of canvas or fabric wrapped in spiral formation and impregnated with rubber or other waterproof composition. Said plugs are adapted to engage firmly with the ground or pavement and thus prevent slipping of the user when the heel is in use. The plugs 12 are spaced apart so as to leave a transversely extending strip 100 13 between the same of rubber or other flexible material of which the body of the heel is formed. This transversely extending flexible portion 13 permits of the heel being flexed along this line to facilitate attachment 105 of the same to the shoe. The flexing results from holding the heel between the thumb and the two first fingers of the hand and flexing the heel in a manner such that the lugs 10 will be in a plane below the central 110 portion of the upper portion of the heel. The heel is held in this flexed condition

until the central portion contacts with the shoe whereupon the ends of the heel are released permitting of the lugs 10 engaging the sockets 11. Without this flexing of the heel in applying the same, great difficulty would be experienced, inasmuch as without this flexing, during each rotation of the heel, the lugs 10 would enter the sockets 11 and thus arrest rotation. It will thus be seen that the flexing of the heel in applying the same is of considerable advantage, and hence the provision of the intermediate portion 13 of flexible material between the non-flexible plugs 12 is highly important.

15 While I have illustrated and described the preferred form of construction for carrying my invention into effect, this is capable of variation and modification without departing from the spirit of the invention. I 20 therefore, do not wish to be limited to the precise details of construction set forth, but desire to avail myself of such variations and modifications as come within the scope of the appended claims.

25 Having described my invention, what I claim as new and desire to secure by Letters Patent is:

1. In combination with a shoe, a heel body having a normally concave upper surface; 30 an annular member embedded in said heel body adjacent the periphery thereof; a resilient cross piece embedded in said heel body and having its ends connected with said annular member; and an exteriorly extending screw connected with said cross piece and removably securing said heel body to said shoe, and binding said cross piece under the compression, substantially as described.

35 2. In combination with a shoe, a heel body

having a normally concave upper surface; an annular member embedded in said heel body adjacent the periphery thereof; a resilient plate embedded in said heel body and having its ends connected with said annular member; and an exteriorly projecting screw connected with said plate and removably securing said heel body to said shoe and binding said plate under compression, substantially as described. 45

50 3. In combination with a shoe, a heel body having a normally concave upper surface; a wire embedded in said heel body adjacent the periphery thereof; a resilient cross piece embedded in said heel body and having its ends connected with said wire, and an exteriorly projecting screw engaged with said cross piece and removably securing said body to said shoe and binding said cross piece under compression, substantially as described. 55

60 4. In combination with a shoe, a heel body having a normally concave upper surface; an annular member embedded in said heel body adjacent the periphery thereof; a resilient plate embedded in said heel body and having its ends connected with said annular member; and exteriorly projecting lugs on said annular member at opposite sides thereof for engagement with lug sockets provided in the adjacent side of said shoe, substantially as described. 65

70 In testimony whereof I have signed my name to this specification in the presence of two subscribing witnesses.

JOHN WILLIAM SMITH.
